Charles A. Wheatley — INVENTOR

BY *Victor J. Evans*

UNITED STATES PATENT OFFICE.

CHARLES A. WHEATLEY, OF JEFFERSONVILLE, INDIANA.

ACTION FOR PLAYER PIANOS.

Application filed November 18, 1920. Serial No. 423,925.

To all whom it may concern:

Be it known that I, CHARLES A. WHEATLEY, a citizen of the United States, residing at Jeffersonville, in the county of Clark 5 and State of Indiana, have invented new and useful Improvements in Actions for Player Pianos, of which the following is a specification.

This invention relates to improvements 10 in the construction of pneumatic actions for player pianos and has for its object the provision of an action so constructed that all the individual valve members are separately detachably mounted beneath and associated 15 with the tube rail, the advantage of the specific structure being that in the event that repairs to the mechanism are necessary the defective valve member may be removed separately or individually without in any way 20 involving any disturbance of the other valve members and thereby making a great saving of time in repair work.

An important object is the provision of 25 an action of this character in which all the valve members are duplicates of a certain unit so that all the valve members will be interchangeable.

Another object is the provision of a mechanism in which the pneumatics are connected 30 with the wippen instead of with the abstract as is the common arrangement.

An additional object is the provision of 35 a device of this character which will be simple and inexpensive in manufacture and installation, highly efficient in use, durable in service, and a general improvement in the art.

With the above and other objects and advantages in view, the invention consists in 40 the details of construction to be herein-after more fully described and claimed and illustrated in the accompanying drawings in which

Figure 1 is a cross sectional view through 45 a player action showing one of my valve members in position,

Figure 2 is a detail sectional view showing 50 the valve members separated from the remainder of the device.

Referring more particularly to the drawings in which is illustrated a single motor pneumatic, the numeral 1 designates a bellows having a movable lift 2 which carries 55 an arm 3 to which is connected a threaded rod 4 slidable through a guide 5 and connected with a block 6 having a felt face 7

engaging the wippen 8 to which is connected the abstract 9 connected with a capstan screw 10 carried by the key 11. The numeral 12 designates the stationary lift 60 which is supported beneath a valve box indicated broadly by the numeral 13. At the front of the valve box is a member 14 above which is the tube rail 15 supported by a block 16. Within the member 14 is the air chest C. 65 The tube rail 15 extends at right angles to the rear wall of the front member 14 and the stationary lift 12 of the bellows extends in spaced parallel relation to the tube rail 15 which provides a rectangular space between 70 these three members.

The rail 15 is provided, of course, at the proper intervals with passages 17 in the forward ends of which lead tubes 18 adapted for connection with a tracker bar and 75 from the rear ends of which extend tubes 19.

The front bar 14 is of course provided with passages 20 which communicate with the rectangular space above referred to and with the interior of each bellows member 80 through a hole 12^a. The position of the movable lift 2 with respect to the stationary lift 12 may be regulated by means of a nut on the rod 4.

It is of course necessary to provide a plurality of valve members, one for each note or hammer of the piano mechanism and one of such valve members is indicated broadly by the numeral 24. Each valve member 24 comprises a rectangular block 25, an upper 90 plate 26, and a bottom plate or block 27. The top plate 26 is formed substantially at its center with a hole 28 and the block 25 is formed at its upper portion with a passage 29 and at its lower portion with a 95 vacuum chamber 30, a hole 31 being formed in the wall separating this passage and chamber. The lower block or plate 27 is formed with a passage 32, one end of which leads into the chamber 30 through a constricted port 40 and the other end of which carries a tube 33 connected with the tube 19, as by rubber tubing. At one end of the chamber 30 is a hole 30^a communicating and registering with a hole D leading into the 100 air chest C whereby a vacuum may be formed in the chamber.

Fitting within the hole 31 is a metallic valve seat 34 upon the upper end of which seats a fiber valve 35 from which depends a stem 36 passing through the seat 34 and through a guide opening in a bracket 37,

Secured between the block 25 and lower plate or block 27 is a diaphragm 38 carrying at its center a reinforcing member 39 adapted to engage the lower end of the stem 36. The valve assembly may be held in the valve box by any suitable means such as the screws S.

The operation of my device is as follows:

The normal position of the valve 35 is as shown in the drawings, but when a perforation of the traveling note sheet, not shown, registers with the tracker bar aperture with which the tube 18 is connected, the resulting impulse of air through the channel 32 fills the space below the diaphragm 38 and lifts the diaphragm and consequently the stem 36 which will result in lifting the valve 35 off its seat 34 so that it will close the opening 28 in the top plate 26. The interior of the motor pneumatic is thereby cut off from the outer air and connected with the vacuum chamber 30, resulting in the collapse of the movable leaf of the bellows and the operation of the corresponding wippen and consequently the key.

The essential feature of the present invention is the fact that the entire valve member formed by the block 25 and plates or blocks 26 and 27, with all the associated parts, constitutes a separate unit or entity which may be removed from or replaced within the rectangular opening defined by the tube rail, front bar, and stationary leaf 38 without in any way interfering with the other units, any suitable screws or the like

being provided for holding each valve member in position.

From the foregoing description and a study of the drawings it will be apparent that I have thus provided a simply constructed and yet highly efficient motor pneumatic mechanism which will be a great time and labor saver when repairs are necessary to a player action.

While I have shown and described the preferred embodiment of my invention, it is of course to be understood that I reserve the right to make such changes in the form, construction, and arrangement of parts as will not depart from the spirit of the invention or the scope of the subjoined claim.

Having thus described my invention, I claim:

In a pneumatic action for player pianos, a tube rail formed with passages each connected with a tracker bar opening, a front bar formed with passages, a bellows including a stationary leaf secured below said front bar and a movable leaf connected with said first named leaf, the second named passages communicating with the interior of the bellows member, and a series of valve members all similarly disposed against said front bar and between the tube rail and stationary leaf, said valve members being individually removable and replaceable and each being provided with a diaphragm actuated valve.

In testimony whereof I affix my signature.

CHARLES A. WHEATLEY.
